UNITED STATES PATENT OFFICE.

SAMUEL E. KALLENBAUGH, OF MANCHESTER, GEORGIA, ASSIGNOR TO KALLENBAUGH CORPORATION.

WEB-FEEDING ATTACHMENT FOR JOB PRINTING PRESSES.

Application filed July 11, 1927. Serial No. 204,957.

This invention is a novel improvement in web feeding and cutting attachments for job printing presses and its objects are to provide a simple attachment whereby, when desired, 5 webs can be printed on ordinary job sheet printing presses and may be severed into sheets; or if desired can be re-wound into roll form and reprinted before severing into sheets, if it is desired to perfect the web by 10 repeated operations of the press.

A further object is to provide means whereby the web may be divided longitudinally into a plurality of longitudinal sections by perforators or slitters before it is severed 15 into sheets, thus enabling a plurality of small sheets or jobs to be simultaneously printed on the press.

In the accompanying drawings I have illustrated the attachment as applied to a 20 Chandler and Price job printing press, although it is applicable to other types of job presses; but the description of the attachment as applied to said press will enable others to readily adapt and use the same. I 25 refer to the claims for summaries of the novel features of construction and novel combination of parts for which protection is desired.

In the drawings,—

Figure 1 is a side elevation of a job printing press with my attachment attached thereto;

Fig. 2 is an opposite side elevation thereof;

Fig. 3 is an enlarged detail view of the web slitting devices;

Fig. 4 is an enlarged detail view of the web severing devices;

Fig. 5 is an enlarged detail view of the web forwarding devices;

Fig. 6 is a detail sectional view of the web 40 rewinding devices.

The job press shown is a type having an approximately vertical platen P and opposed vibrating bed B which is moved to and from the platen by means of pitmen A which connect the bed supporting member with crank pins c on crank disks C which are mounted on a shaft driven in the usual manner from a main driving shaft D carrying a flywheel W; as these parts are all old and well known they

45 need no description or illustration.

The sheets to be printed are usually fed by hand between the bed and the platen and are impressed by the pressing together of the bed and platen, one sheet being printed for

each rotation of the shaft carrying the disk C. 55

My attachment comprises a frame of any suitable construction on which the operative parts are mounted, said frame being shown as approximately rectangular and of a width approximating the width of the press. This 60 frame can be disconnectably attached to the press at one end by any suitable means, angles 2 and bolts 3 being shown, by which the frame may be bolted to the table T of the press. 65

The frame is provided with bearings 4 for the shaft 5 of a paper roll W' and the web w is led from this roll W' under an idler tensioning roller 6 which is mounted in swingable bars 6^a pivoted to the frame. 70

The web then passes to and under a guide roller 7 which is mounted in the ends of bars 1^a attached to the frame; said bars being of such extent, that the web w can be led upward from the roller 7 to and between the 75 platen P and bed B, the web lying close to the face of the platen, and above the platen to and over a roller 8 which is mounted in bearings in side pieces 9, attached to side members 9^b which are hinged at 1^c to the top 80 members 1^b of the frame, as indicated in the drawing. The roller 8 can be adjusted vertically so as to lengthen or shorten the length of web between the roller 7 and the feed rollers hereinafter referred to. As shown the 85 roller 8 can be vertically adjusted by means of screws 9^c which are interposed between the side members 9^b and the table T.

Above and co-acting with the roller 8 is a roller 10 which is preferably journaled in bearings 10^a adjustably mounted in the side pieces 9, so that the roller 10 can be adjusted toward or from the roller 8. This adjustment being effected by screws 10^b. The rollers 8 and 10 may be provided with perforating or 90 slitting devices as hereafter explained, if it is desired to divide the web into longitudinal sections before reaching the cutting devices. 95

From roller 8 the web W is led to and between feed rollers 11 and 12, the shafts of 100 which rollers are journaled in bearings in members 1^f attached to the sides of the main frame as shown. The feed rolls are operated to feed the paper by suitable means. As shown a ratchet wheel 11^a is keyed to the shaft of feed roll 11, at one end thereof, and an arm 11^b is pivoted on the shaft beside this ratchet 105 11^a said arm carrying a plurality of pawls 11^c.

(Fig. 5) which are adapted to engage the ratchet wheel 11^a. The arm 11^b has an adjustable pin-and-slot connection indicated at 11^c, with one end of a link 13, the other end 5 of which is connected by a pin-and-slot connection, indicated at 13^a, with a slotted yoke 14 fixedly attached to one of the disks C. Preferably this slotted yoke 14 is connected to the crank pin c at one side of the pitmen A. 10 By this means for each rotation of the disk C, and each operation of the press, the lever 11^b is oscillated, and the parts are so adjusted that the web is fed forward between impressions and is stopped during the taking of an 15 impression. The intermittent feed of the web is effected by the link 13 connecting the lever 11^b with the yoke 14. By adjusting the connections between the link 13 and the lever 11^b or the link 13 and the yoke 14, or both, any desired 20 variation in the length of the web fed between impressions can be obtained; so that only the proper length of web (according to the length of form being printed plus margins between impressions) will be fed at each 25 operation of the press.

The roller 12 may consist of a shaft and adjustable trolley rollers 12^a as shown in Figure 5. When such trolley rollers are used, they are preferably rotatable idly of the 30 shaft, and may be adjusted longitudinally thereof and confined in adjusted position between collars 12^c which can be secured to shaft when adjusted by set screws 12^d, see Fig. 5. The pressure of the trolleys on the 35 roller can be adjusted by a set screw indicated at 12^e.

The feed rollers 11 and 12 direct the web outwardly past a cutting device which may be of any suitable kind, as shown. It 40 comprises an oscillating blade 15 and a co-acting fixed shearing blade 16. The blade 16 is mounted on a transverse member 1^c of the main frame adjacent the feed rolls, and the blade 15 is shown as pivoted at one end on a stud 15^a and its other end is connected by a 45 rod 15^b to a lever 16 (Fig. 1) which extends beyond the shaft D and beside one of the disks C, and is pivoted at 16^c to the upper end of a swingable lever 16^b which is pivoted 50 at 16^c to one side member of the press. The bar 16 may be provided with a wear plate 16^e which is adapted to be engaged by a roller 16^f on the pin c or by the rounded end of the 55 pitman A connected to said crank pin c. By pivoting the lever 16 to the swingable lever 16^b the knife is not affected by the arcuate swing of the lever 6, and the knife is kept in position to effectively shear with the blade 16 by means of a spring 15^e connected to the rod 60 15^b and to an adjacent part of the frame. The knife is normally held in raised position by means of a spring 16^g connected to lever 16 and to an adjacent part of the frame. These parts are so proportioned and positioned that the knife is actuated once for

each operation of the press; and the knife is actuated to sever the web between impressions at a time when the web is stopped.

The sheets severed by the knife 15 fall upon a table 17 in the frame. In case it is not desired to sever the web into sheets, the web or strips of web may be re-wound on a re-winding shaft 18 which is mounted on suitable bearings on the frame at a point beyond the knife. When the web is to be re-wound the 75 knife 15 is put out of action by disconnecting the rod 15^b from the knife. This can be readily done in various ways. As shown the upper end of rod 15^b has an eye which is engaged with a stud 15^a on the free end of the knife 15, and the rod 15^b is detachably held in engagement with the stud by a cotter pin 15^c.

When it is desired to rewind the web the end of the web may be fastened to the shaft 85 18 or to a spool 18^a thereon and this shaft 18 may be rotated by any suitable means. As shown a pulley 18^a on one end of shaft 18 is driven by a loose belt 18^b from a pulley 18^c on the shaft D. This belt device will rotate the roller 18 in the proper direction to wind up the web as it is fed forward by the rolls 11 and 12, but belt will slip when the feed rolls are stopped. If desired after the web printed on one side has been re-wound on the web roll 18, as indicated at W^a, the roll W^a may be removed and placed in the bearings 4 and the web again led through the press and printed on the other side (or perfected) and severed into sheets if desired which will be 100 deposited upon table 17.

When printing tickets or the like the roller 10 may be provided with perforated or cutting disks 10^c, and the roller 8 with cooperating grooved or female disks 8^c, see Figure 3. 105 These disks 10^c, 8^c may be longitudinally adjusted upon the shafts and held in adjusted position thereon by means of collars 10^e, 8^e, respectively; which can be held in adjusted position by means of set screws 10^f, 8^f.

Any desired number of slitters or perforators 10^c, 8^c, may be used, and adjusted as desired, according to the width to be severed from the printed web. This slitting device is used when the machine is employed for printing tickets, or small circulars or pages, a plurality of which can be printed side by side on the web at each operation of the machine.

The re-wind roller 18 may carry spool sections 18^a which can be placed on the shaft 18 so that when the web is re-wound on these spools the re-wound web can be readily removed from the shaft.

What I claim is:

1. In combination with a bed and platen job press having rotatable cranks and pitmen for oscillating the platen; a frame, web guiding rollers mounted upon said frame whereby a web may be led to and through the job press to be printed thereby; a web

- feed roll mounted on said frame, means operable by one of the cranks for operating the feed roll whereby the web may be fed forward after each operation of the press; web severing devices mounted on the frame and a member pivotally mounted on the press and adapted to be oscillated by one of the cranks for actuating the web severing devices. 70
10. 2. In combination with a bed and platen job press having rotatable cranks and pitmen for oscillating the platen; a frame, web guiding rollers mounted on said frame whereby a web may be led to and through the job 75 press to be printed thereby; swingable members pivoted to the frame and supporting the upper web guide roller, and means for adjusting the swingable members; a web feed roll mounted on said frame, means operable by one of the cranks for operating the feed roll, web severing devices mounted on the frame and a member pivotally mounted on the press and adapted to be oscillated by one of the cranks for actuating the web severing 80 devices. 85
15. 3. In combination with a bed and platen job press having rotatable cranks and pitmen for oscillating the platen; of a frame, a web roll support mounted on said frame, web 90 guides for directing the web from the web roll to and between the platen of the press, a web feeding roll mounted on the frame, an oscillating member for actuating said feed roll; an adjustable connection between the member and one of the cranks to vary the feed of the web; a knife for severing the web mounted on the frame, a lever pivotally mounted on the press and adapted to be oscillated by one of the cranks, and a rod connecting this lever with the knife. 95
20. 4. In combination with a bed and platen job press having rotatable cranks and pitmen for oscillating the platen; a frame, a web roll support mounted on said frame, web guides for directing the web from the web roll to and between the platen of the press; swingable members pivoted to the frame and supporting the upper web guide roller and means for adjusting the swingable members; a web 100 feeding roller mounted on the frame, an oscillating member for actuating said feed roll; an adjustable connection between the member and one of the cranks to vary the feed of the web; a knife for severing the web mounted on the frame, a lever pivotally mounted on the press and adapted to be oscillated by a pin on one of the crank disks, a rod connecting this lever with the knife; a spring for retracting the knife and lever; and web slitting devices on the frame. 105
25. 5. In combination with a bed and platen job press having rotatable cranks and pitmen for oscillating the platen; of an attachment comprising a frame, a web roll support on said frame, web guides for directing the web from the web roll to and between the platen of the press, a web feeding roll on the frame, 110 means for actuating said feed roll from a member of the press; means on the frame for severing the web operable by a member of the press; and web slitting devices on the frame. 115
30. 6. In combination with a bed and platen job press; an attachment comprising a frame, a web roll support mounted on said frame, web guides for directing the web from the web roll to and between the platen of the press, a web feeding roll mounted on the frame, an oscillating member for actuating said feed roll; an adjustable connection between the member and a member of the press to vary the feed of the web; a knife for severing the web mounted on the frame, a lever pivotally mounted on the press and adapted to be actuated by a member of the press, and a rod connecting this lever with the knife; and web slitting devices on the frame. 120
35. 7. In combination with a bed and platen job press having rotatable cranks and pitmen for oscillating the platen; a frame detachably connected to the press frame, a web roll support mounted on said frame, web guides for directing the web from the web roll to and between the platen of the press; a web feeding roller mounted on the frame, an oscillating member for actuating said feed roll; an adjustable connection between the member and one of the crank disks whereby the web may be fed forward after each operation of the press; a knife for severing the web mounted on the frame, a lever pivotally mounted on the press and adapted to be oscillated by a pin on one of the crank disks, a rod connecting this lever with the knife; a spring for retracting the knife and lever; and web slitting devices on the frame. 125
40. 8. In combination with a bed and platen job press having rotatable cranks and pitmen for oscillating the platen; a frame detachably connected to the press frame, a web roll support mounted on said frame, web guides for directing the web from the web roll to and between the platen of the press; swingable members pivoted to the frame and supporting the upper web guide roller and means for adjusting the swingable members; a web feeding roller mounted on the frame, an oscillating member for actuating said feed roll; an adjustable connection between the member and one of the crank disks whereby the web may be fed forward after each operation of the press; a knife for severing the web mounted on the frame, a lever pivotally mounted on the press and adapted to be oscillated by a pin on one of the crank disks, a rod connecting this lever with the knife; a spring for retracting the knife and levers; and web slitting devices on the frame. 130
45. 9. In combination with a bed and platen job press having rotatable cranks and pitmen for oscillating the platen, a frame, a web roll support on said frame, a web tightening

roll pivoted to said frame operable by its own weight, web guides for directing the web to and through the press, a web feed roll mounted on the said frame, an oscillating member for actuating the feed roll, an adjustable member between the oscillating member and one of the cranks of the press, and means on the frame for severing the web operable by one of the cranks of the press; 5 the web guides including a roll adapted to be elevated or lowered on the said frame between the platen and the web feed roll to facilitate adjusting the web so that the impression will be in proper position with respect to the severed edge.

10. In combination with a bed and platen job press or the like an attachment comprising a frame, a web support mounted on said frame, a gravity controlled tension roll pivoted so as to maintain a constant pressure on the web as it unwinds from the web roll, web guides for directing web to and through the press, a web feed roll mounted on said frame, an oscillating member for actuating said roll, 20 an adjustable connection between the member and one of the pitmen of the press to vary the feed of the web, a knife for severing the web mounted on the frame, a lever pivotally mounted on the press and adapted 25 to be actuated by one of the cranks of the press, a rod connecting said lever with the knife, the web guides including a roll adapted to be elevated or lowered on said frame between the platen and the web feed roll to 30 facilitate adjusting the feeding of the roll with respect to the knife, and means for elevating or lowering said guide roll.

11. In combination with a bed and platen job press or the like, an attachment comprising

ing a web support adapted to be secured to any suitable foundation immediately in front of the press, a gravity controlled roll held by arms pivotally connected to said support, a frame stationed between the web support and the press, web guides on said frame to direct the web to and through the press, a web feed roll mounted on said frame, an oscillating member for actuating said web feed roll, an adjustable connection between the member and one of the cranks of the press to 40 vary the feed of the web, a knife for severing the web mounted on the frame; a lever pivotally mounted on the press, and means for connecting said lever with the knife, the web guides including a roll adapted to be 45 elevated or lowered on the frame between the platen and the web feed roll to facilitate lengthening or shortening the portion of the web between the platen and the web fed roll.

12. In combination with a bed and platen job press or the like, an attachment comprising a frame, a web support immediately in front of said frame, a gravity controlled tension device adapted to rest upon the web as it unwinds from the web roll, guides for directing the web to and through the press including, a guide roll adapted to be elevated or lowered on said frame immediately above the platen of the press, a web feed roll mounted on said frame, an oscillating member actuating the feed roll, an adjustable connection between said member and one of the pitmen of the press, web slitting devices mounted on the frame, and means for severing the web.

In testimony that I claim the foregoing as 75 my own, I affix my signature.

SAMUEL E. KALLENBAUGH.
